APPARATUS FOR SUPPORTING AND SPACING REINFORCING DEVICES

Ralph D. Yankee, Kansas City, Mo.

Application March 20, 1941, Serial No. 384,316

9 Claims. (CL 72—122)

This invention relates to apparatus for supporting and spacing reinforcing devices for structural elements, the principal objects of the present invention being to provide a convenient, economical and efficient apparatus for the purpose noted.

One of the chief problems encountered in erecting buildings and like structures is to reconcile an architect's rigid requirements in accuracy of structure and appearance of the intended structure with the contractor's desire to erect the structure as cheaply as possible with the labor available. A time element is also usually involved in the erection of a structure and it is obviously to the contractor's advantage to be able to erect a building in a minimum amount of time without sacrificing quality or strength.

Other objects of the present invention are, therefore, to provide apparatus by which architects' specifications may be scrupulously followed, and by which the work of the men on the structure, under direction of the contractor, is materially facilitated by allowing speeding up of the work, reducing makeshift practices in the work, requiring less actual work to be done, and allowing a better job to be accomplished.

The iron workers' procedure in placing reinforcing steel in beams, joists, slabs, and the like, in constructing a building is to set stirrups at measured distances, as specified by the architect in his blue prints, in the beam end adjacent the column; stringing the tops as near that spacing as possible by anchoring loose wires on both sides of the beam at the column and looping each individual stirrup, and when all are strung, again anchoring the loose wires to a nail driven in a form. Beam bolsters are then placed throughout the beam or joist or slab form, on which are placed the reinforcing rods, whatever be their shape as designed by the architect. The rods are spaced and secured as well as possible by tying at numerous points to the bolsters. Then each individual stirrup is tied up to the main reinforcement at two places to enable them and the rod network thus formed to be supported free of the forms.

This present method is not accurate and requires much tying to secure the desired result. The traffic of workmen and impacts during construction usually causes the reinforcement to be displaced from desired position, and in some cases, where the loose wires have to be cut to allow introduction of other reinforcement, portions of the work collapse, thus entailing much more work to restore to original form or, if neg-

ligently overlooked, the functions desired by the architect are not met.

The reinforcement is also not supported away from the forms, nor is it completely surrounded by concrete. Furthermore the reinforcement is so out of position that the network will not test to the intended strength or strain resistance.

Therefore, I have invented an apparatus for supporting and spacing the stirrups and rods in beams, joists, slabs and the like, of such a character that the architects' spacing may be accomplished accurately as designed and intended; an apparatus so complete and thorough that reinforcement will stay placed despite workmen traffic and construction impacts; an apparatus which eliminates a material amount of the tying and all of the stringing, thus allowing complicated placements without interference, and which, if overlooked and not tied at all, still gives a better job and a nearer approach to specifications than at present accomplished.

I have also provided an apparatus, the component steps and parts of which are cheaper to put into practice than present types, thus reducing the total cost of a job, pleasing the architect by its accuracy and security, and pleasing the contractor by reduction in labor costs of stringing and tying, which latter are sometimes enormous in deep, difficult or complicated beams, joists, slab and like forms.

This apparatus, and the functions desired of it, are secured by using a driving member, as hereinafter described in detail, somewhat similar to an ordinary fence staple, but of a particular design and shape adapted to the job, working in cooperation with a spiral spring with removable cores, the shape and weight of which are determined by the weight and size of the various portions of the reinforcement work that is to be placed in beams, joists, slabs and the like.

This method and apparatus does the whole job of supporting and spacing reinforcement work, the steps and elements cooperating together in the arrangement of beams, joists, slabs and the like, in such a manner that where there are numerous stirrups more driving members are needed than spring types of bolsters, and vice versa, i. e., where stirrups are fewer or absent more spring type bolsters are used.

This apparatus also provides a very simple and easy way to tie in reinforcements when a minimum of tying is absolutely essential. All members are easily adapted as to length or size

in the field with fewer types than in other methods now in use.

Other objects of the invention are to provide for properly positioning the reinforcing devices of the structural elements and also maintaining them in desired position regardless of the usual amount of worker traffic, jarring impacts and similar interferences with the proper placement and maintenance of such reinforcing devices; and, further, to provide improved elements and arrangements thereof in the placement of the improved reinforcing elements in an apparatus of the character noted.

In accomplishing these and other objects of the present invention, I have provided improved details of structure, the preferred forms of which are illustrated in the accompanying drawings, wherein:

Fig. 1 is a perspective view showing a structural element form, partly in vertical cross-section, provided with reinforcing elements and supports and spacers therefor, which constitute an embodiment of this invention.

Fig. 2 is a vertical cross-sectional view through a structural element showing the relation of the reinforcing devices and my supports and spacers therefor, relative to such structural element.

Fig. 3 is a vertical transverse cross-sectional view substantially on the line 3—3, Fig. 2.

Fig. 4 is a plan view of the form, structural reinforcing element, supports and spacers therefor illustrated in Fig. 1.

Fig. 5 is a perspective view of a beam spacer embodying a feature of the present invention.

Fig. 6 is an end elevational view of a beam spacer showing the relation thereof to beam reinforcing elements and a beam, the form, beam and reinforcing elements being shown in transverse, vertical cross-section.

Fig. 7 is a detail perspective view of a slab spacer embodying a feature of this invention.

Fig. 8 is an end elevational view of the slab spacer, the flat band core being shown in vertical cross-section and the slab reinforcing element being shown diagrammatically.

Fig. 9 is a side elevational view of the slab spacer illustrated in Figs. 7 and 8.

Fig. 10 is an end elevational view of the stirrup spacer illustrated in Figs. 11 and 12.

Fig. 11 is a perspective view of a form of stirrup spacer embodying a feature of this invention, a portion of a stirrup being shown diagrammatically, in supported relation to the stirrup spacer.

Fig. 12 is a side elevational view of the stirrup spacer illustrated in Fig. 11.

Referring more in detail to the drawings:

1 generally designates a form for beams, joists, slabs and the like, which in this instance comprises a bottom wall 2, side walls 3 and 4, and upper walls 5 and 6 for defining a space 7 into which concrete or similar material may be poured or otherwise placed in such a manner as to form a beam, slab, joist or other suitable structural elements.

As above pointed out, one of the principal features of this invention is the facilitation of placement of reinforcing devices relative to structural elements and to this end, taking beams as an example, stirrups 8 are employed, which stirrups generally consist of approximately the U-shaped devices shown having side arms joined by a base member 9 and having upper, laterally extending hooks 10 and 11 for hooking into a slab related to the beam being formed:

In order to facilitate placement of the stirrup 8 and maintenance thereof in desired position stirrup spacers 12, Fig. 1, and/or 13, Figs. 10, 11 and 12, are provided. The principal requisite of the stirrup spacers are that they be provided with an eye 14 of sufficient size to easily pass any of the portions of the stirrup 8 in such a manner that they may be sleeved on the stirrup in supporting relation to the several parts thereof. The stirrup spacers should have at least one post 15 provided with an end 16 capable of embedment in a form, such as 1, Fig. 1, and indicated generally in Fig. 1 as at 16.

It is sometimes desirable to obviate sleeving of the stirrup spacers over the stirrups, and to this end I prefer to provide the stirrup spacers with a double post, shank or foot, as at 17, for augmenting the effect of the foot member or post 15. These cooperative foot members provide a more stable support for the stirrups on which they are threaded, sleeved or placed. The foot members 15 and 17 are related to the eye 14 of the stirrup spacer in such a manner as to allow application of the spacers to the stirrups intermediate the ends thereof as by the provision of a space 18, Fig. 10, between the ends of the foot members at their junctures 19 and 20, with the extremities of the eye 14. With this arrangement it is apparent that the foot members may be arranged straddle-wise of a portion of a stirrup and pressed or struck, as with a hammer, in the direction of the stirrup. When the stirrup spacer is aided in movement in the noted direction, as by a light impact with a hammer or the like, the stirrup spacer easily passes over the portion of the stirrup desired. The stirrup spacers are preferably formed of a material having an inherent resiliency which allows an initial spreading thereof to pass over the stirrups and then causes the stirrup spacer to resume its substantially normal condition in sleeved relation to the stirrup.

The foot members are preferably arranged to cross each other, as indicated at 21, in Figs. 11 and 12, in such a manner that the junctures of the foot members with the eye of the spacer form spaced supports for portions of the stirrups. This is a material advantage for the reason that the stirrup has substantial support on the spacer, and the spacer foot members, when both are embedded in the form, provide a stable and substantial support capable of adequately spacing the stirrups and holding them in desired position without collapsing as a consequence of accidental impacts, stepping upon them, or other difficulties encountered in the normal routine of the workers erecting the structure of which this invention is to form a part.

After placement of the stirrup in the form, reinforcing bars, such as the bar 22, Fig. 1, of rectangular cross-section and/or bars 23 of circular cross-section are mounted longitudinally in the form 1 in such a manner as to rest upon the bases 9 of the stirrups 8, as shown at 24, Fig. 1, 25, Fig. 2, and 26 and 27, Fig. 3. It is desirable that the bars 22 and/or 23 be adequately supported longitudinally thereof and preferably in upwardly spaced relation to the bottom wall 2 of the form in such a manner that they do not show below the beam after concrete has been poured into the form, and thus allow presentation of a better appearing structure as well as aiding in the erection of a strong structure. The stirrup spacers arranged on the bases of the stirrups as shown in Figs. 1, 2 and 3, hold the stirrup in upwardly spaced relation to the bottom wall of the

form, and consequently also hold the bars 22 and/or 23 in that arrangement in a convenient, economical and efficient manner.

Proper placement of the stirrups ordinarily requires a great deal of work. The present arrangement obviously substantially reduces the amount of work ordinarily involved in the placement of the stirrups by eliminating stringing at the top and also bottom tying. It is also apparent that the tying of rods relative to the stirrups may be accomplished in a very simple manner.

It has been found desirable in some instances to reduce the number of stirrups that normally would be required to adequately support the structural member reinforcing elements. I, therefore, provide a cooperative spacer and/or bolster relative to the stirrup or stirrups that acts concurrently with and as an adjunct to the stirrups in cooperatively supporting the reinforcement bars and at the same time spaces the same and holds them in desired relation to each other and to the stirrups.

The beam spacer and/or bolster 28 illustrated in Figs. 5 and 6, is an illustrative embodiment of this form of cooperative spacer and/or bolster relative to the stirrup. The preferred arrangement of this beam spacer-bolster 28 is embodied in a spiral spring 29 that is capable of being rolled into place, the spring having suitable resiliency and spaces 30 between the coils thereof for allowing the bars 22 and 23 to be arranged in desired spaces 30 between the spirals 29 of the spring under tension of the coils in such a manner as to hold the bars in place, as illustrated in Figs. 1, 2, 4 and 6.

The bars 20 or 21 are given transverse support supplemental to the bases of the stirrups by a core 31 for the spring, the preferable arrangement of the core being a bar of circular cross-section and having a length of approximately the width of the form 1. The core 31 is preferably arranged loosely within the spring and is thus arranged on the bottom of the spring subsequent to rolling the spring into desired position. The core 31 is preferably of sufficient diametrical cross-section to support the bars 22 or 23 in the same plane as the support of the bars by the stirrups.

If desired, adjacent coils of the spring spacer-bolster may be tied, as indicated at 32, Fig. 6, in order to positively retain the bars between such coils in supported and spaced relation to each other.

In practicing my invention with the suggested apparatus above referred to, for example, in the construction of a beam, the stirrups are substantially positively applied to the form in suitable numbers as by the stirrup spacers illustrated, and this preferably without the use of guide wires normally employed in structures of this type heretofore available. Depending upon the number of stirrups employed, the beam spacer-bolsters 28 are placed at intervals between the stirrups and the reinforcing rods are applied to suitable spaces between the coils of the beam spacer-bolsters, and are thus resiliently held in desired position.

The beam spacer-bolsters and stirrups are related, in that both act together and supplement the action each of the other. The more stirrups that are used the less number of beam spacer-bolsters are necessary, and vice versa. The stirrups and the beam spacers both act together in properly arranging the reinforcing rods vertically and laterally relative to the form and the

beam formed therein. When concrete is poured into the form, all of the reinforcing elements and/or supports therefor that can be exposed through the beam are mere points or lines, as distinguished from substantial surfaces. A better looking and stronger structure is thus provided.

Joist and slab constructions can be arranged in substantially the same manner and with substantially the same advantages with the modified form of structure illustrated in Figs. 7 to 9, now to be described in detail.

The form of spacer-bolster illustrated in Figs. 7 to 9 is substantially similar to that illustrated in Fig. 5, with the exception that it is preferably lighter in the spring portion 35, and the core 36 thereof is preferably of a different arrangement from the core 31 of the spacer-bolster 28. In the present instance, the core 36 constitutes a flat band that is removably arranged in the interior of the spring. The side edges 37 and 38 of the band contact portions of the interior of the spring to maintain the band in spaced relation to the bottom of the form in which it is placed. This arrangement provides for space 39 below the band and spaces 40 and 41 at the sides of the band between the spacer-bolster coils that allow material, such as concrete, to easily pass by the spacer-bolster and accumulate below the core. It is apparent that the core may be perforated, if desired, to further facilitate placement of concrete and the like underneath the core during pouring of concrete in the form, in which the spacer is arranged.

Practice of the present invention may be carried out with the forms of spacer-bolster illustrated in Figs. 7 to 9, in a manner substantially similar to that referred to in connection with the form of invention illustrated in Figs. 1 to 6, inclusive, and Figs. 10 to 12.

It is apparent, therefore, that I have provided by the present invention, a method and apparatus that greatly facilitates the construction of monolithic structural elements; that accurately places reinforcements for such elements and adequately supports the same; and, further, that architects' specifications may be conveniently, economically and efficiently conformed to by contractors.

What I claim and desire to secure by Letters 50 Patent is:

1. In an apparatus of the character described, a form, stirrups, means for substantially positively applying the stirrups in spaced relation longitudinally of and in the form, a bolster consisting of a wire spiral having convolutions provided with a core extending therethrough in spaced relation to the upper portions of the convolutions and loosely mountable in the form in spaced relation to the stirrups, reinforcing elements arranged longitudinally of the form and adapted for concurrent support by the bolster and stirrups collectively, whereby the reinforcing elements are resiliently held in spaced relation between the convolutions of said spiral, and means for tying portions of said spiral portion of the bolster to substantially positively retain the reinforcing elements in desired position relative to the spiral member.

2. In an apparatus of the character described, a bolster adapted for loose mounting in a form to aid in supporting a reinforcing element comprising a spiral spring, and a core loosely mounted in the spring, said core consisting of a relatively flat band arranged within the spring, the sides 70 of said band engaging portions of the spring to

retain the band in upwardly spaced relation to the form.

3. In an apparatus of the character described, a form, stirrups, means for substantially positively applying the stirrups in spaced relation longitudinally of and in the form, a bolster consisting of a wire spiral provided with a core extending therethrough loosely mountable in the form in spaced relation to the stirrups, reinforcing elements arranged longitudinally of the form and adapted for concurrent support by the bolster and stirrups collectively, whereby the reinforcing bars are resiliently held in spaced relationship between the convolutions of said spiral and are supported above the bottom of said spiral by said core.

4. In an apparatus of the character described, a form, stirrups, means for applying the stirrups in spaced relation longitudinally of and in the form, a bolster loosely mountable in the form in spaced relation to the stirrups, said bolster consisting of a spiral member provided with a core extending therethrough, and reinforcing elements arranged longitudinally of the form and adapted for concurrent support by the bolster core and stirrups collectively, said core being supported in spaced relation to the form by portions of said spiral member.

5. In an apparatus of the character described, a form, stirrups, means for applying the stirrups in spaced relation longitudinally of and in the form, a bolster loosely mountable in the form in spaced relation to the stirrups, said bolster consisting of a spiral member provided with a core extending therethrough, and reinforcing elements arranged longitudinally of the form and adapted for concurrent support by the bolster core and stirrups collectively, said core being supported in spaced relation to the form by portions of said spiral member, said spiral member resiliently retaining the reinforcing elements in laterally spaced relation.

6. In an apparatus of the character described, a form, bolsters loosely mountable in the form in longitudinally spaced relation, said bolsters each consisting of a wire spiral provided with a core extending therethrough and positioned at

the bottom of said wire spiral, and reinforcing elements arranged longitudinally of the form and adapted for concurrent support by the bolster cores collectively, portions of the wire spiral engaging the reinforcing elements to hold said elements in spaced relation.

7. In an apparatus of the character described, a form, stirrups, means for substantially positively applying the stirrups in spaced relation longitudinally of and in the form, a bolster consisting of a wire spiral provided with a core extending therethrough and mounted in the form in spaced relation to the stirrups, and reinforcing elements adapted to be supported concurrently by the stirrups and bolster core, whereby the reinforcing elements are resiliently held in spaced relation between the convolutions of the spiral and are supported above the bottom of the spiral by means of said core.

20 8. In an apparatus of the character described, a form, rollable bolsters loosely mounted in spaced relation in the form, said bolsters consisting of a wire element having circular convolutions engaging the form, a core extending through said convolutions and supported in spaced relation to the form by portions of the wire element, the convolutions of said wire element having portions extending above the core, and reinforcing elements supported by the bolster cores collectively and held in spaced relation by the upper portions of said wire element.

9. In an apparatus of the character described, means substantially positively retaining stirrups and the like in desired relation to a form 35 comprising a fastening device constructed of a single piece of wire bent intermediate its length to form an eye-head portion adapted for engagement with a stirrup, said eye-head portion being formed in the shape of a spiral and the ends 40 forming leg portions drivable into a form, the legs being spaced longitudinally of the axis of the eye-head portion to allow said fastening device to be easily placed over said stirrup intermediate the ends thereof in position to be driven 45 into the form.

RALPH D. YANKEE.
